UNITED STATES PATENT OFFICE.

CHARLES P. BRUCH, OF NEW YORK, N. Y.

DESIGN FOR A LETTER-HEAD.

40,529.

Specification for Design.

Patented Feb. 22, 1910.

Application filed November 2, 1909. Serial No. 525,966. Term of patent 14 years.

To all whom it may concern:

Be it known that I, CHARLES P. BRUCH, a citizen of the United States, residing at New York, in the county of New York and State of New York, have invented a new, original, and ornamental Design for Letter-Heads, of which the following is a specification, reference being had to the accompanying drawing, forming part thereof.

The figure is a plan view of a letter head, showing my new design.

I claim:

The ornamental design for a letter head, as shown.

CHARLES P. BRUCH.
